(57) **CLAIM**

The ornamental design for a tool tray for a saw horse, as shown and described.

DESCRIPTION

FIG. 1 is a perspective view of a tool tray for a saw horse incorporating our new design;

FIG. 2 is a top plan view of a tool tray for a saw horse;

FIG. 3 is a front view of a tool tray for a saw horse;

FIG. 4 is a bottom plan view of a tool tray for a saw horse;

FIG. 5 is a rear view of a tool tray for a saw horse;

FIG. 6 is a left side view a tool tray for a saw horse attached to a leg of the saw horse; and,

FIG. 7 is a right side view a tool tray for a saw horse attached to a leg of the saw horse.

The broken lines shown in the drawings illustrate portions of the tool tray for a saw horse that forms no part of the claimed invention.
